AUTOGRAPHIC REGISTER

Aloysius Becker, Hamilton, Ohio, assignor to Paul Benninghofen and F. B. Diesbach, Hamilton, Ohio, as trustees

Application May 17, 1956, Serial No. 585,541

1 Claim. (Cl. 282—16)

This invention relates to autographic registers of the type which employ pin wheels to feed the sets of manifolding stationery, this stationery having feed apertures arranged in lines along the margins into which the pins of feed wheels engage.

In my copending patent applications Serial Nos. 404,547 and 404,561, both filed January 18, 1954, now U.S. Patent No. 2,809,830 and No. 2,793,855 respectively, I have disclosed an autographic register which employs a pair of feed disks and a grip roller to advance sets of manifolding stationery of a different type. In the machine disclosed the stationery is engaged between the grip roller which contacts the upper surface, and the disks which contact the under surface. The roller and disks are driven by means such as a hand crank and they serve to advance the stationery and they also cooperate in a general way to align the superimposed forms in the sets of stationery by virtue of their relationship to pairs of apertures which are located between adjacent sets of forms. One of the advantages of the autographic register disclosed in the copending applications is that it is capable of advancing forms of various lengths without making any modifications or changes in the feeding and aligning mechanism.

The pin wheel type of feed of this application is adapted to be installed in the autographic register disclosed in the applications without substantial changes being made in the general overall construction. Hence one of the objectives of the invention is to provide pin wheel type of feed mechanism for a register of the type disclosed in my copending patent applications.

An important objective of the invention is to provide a feed mechanism which may be employed in an autographic register utilizing manifolding forms in which writing is transferred from one form to another in a set of superimposed forms without the use of conventional carbon paper. In such a transfer the writing pressure of a pencil or a ball point pen, for example, brings the back of the top sheet into intimate contact with the upper surface of the second sheet, and thus so on down through all of the forms in the set. The back of the uppermost sheet is coated with a film which reacts chemically with a receptive coating provided on the upper face on the second sheet. The reaction results in a change of color in the coating on the second sheet below the places where writing pressure is brought to bear on the top sheet so that the words and figures written on the top sheet are transferred onto the second sheet and so on down to the various forms in the set. Since it is pressure which causes the transfer it may be seen that a feed mechanism for an autographic register using such manifolding forms cannot squeeze or press the forms, because to do so would result in dark streaks or marks on all of the forms below the top one. In the autographic register of the copending patent application, the forms are fed between feed disks and a feed roller which would cause dark bands to appear. Thus, a primary objective of the invention is to provide an autographic register which is

2

adapted to feed manifolding forms without exerting any pressure on the forms in the areas thereon in which writing or figures are to appear.

A further objective is to provide an autographic register of the type set forth in which a clamp device is provided to securely lock the forms onto the writing platen at the end of each feeding operation so that the superimposed forms cannot shift with respect to one another while they are being written upon.

10 A further objective of the invention is to provide a pin wheel type of autographic register in which forms of varying lengths can be accommodated by making only a slight change in the feed mechanism.

In substance therefore, the feeding mechanism of this 15 invention adapts a register of the type disclosed in my copending patent applications to a pin wheel type of feed; it exerts no pressure on the forms during feeding, which would cause marks or smudges; and by making only a minor change it adapts the register to forms of various 20 lengths so that the requirements of different users of the autographic register, insofar as form length is concerned, may be met with little difficulty and without adding cost.

Other objectives of the invention will be readily apparent to those skilled in the art from the following detailed description of the drawings in which:

Figure 1 is a fragmentary plan view showing the feed mechanism of this invention.

Figure 2 is a fragmentary cross sectional view taken 30 on the line 2—2 of Figure 1.

Figure 3 is a fragmentary cross sectional view taken on the line 3—3 of Figure 2.

Figure 4 is a diagrammatic view showing a portion 35 only of the feed mechanism during an advance in the feeding part of a cycle of operation.

Figure 5 is a view similar to Figure 4 showing the feeding mechanism at rest at the end of an advancing cycle.

Figure 6 is a diagrammatic view illustrating the change 40 which may be made in the feed mechanism in order to accommodate the register to manifold forms of different lengths.

Inasmuch as the feed mechanism of this invention is 45 adapted to fit into a register of the type shown in copending patent applications to which reference has been made, it is not believed necessary to go into the details of those parts which are not related directly to the invention. In general, however, the feed mechanism is designed to be used in conjunction with a strip of manifolding forms 10 which moves across a writing platen

50 11, the manifolding forms being of the type which have a plurality of evenly spaced small round holes 12 arranged in lines which extend lengthwise of the forms along the two marginal edges. The sets of forms in the strip are defined one from another by perforated lines, 55 such as the one shown at 13, which extend transversely of the strip. The transfer medium employed for the forms is the subject matter of a number of U.S. patents and is now commercially available. For the purposes of this disclosure, it is believed sufficient to state that 60 in the use of such paper in an autographic register no pressure can be brought to bear upon the superimposed forms in a set during the feeding operation.

The present feed mechanism is mounted between two 65 frame members constituted by a pair of upright plates 14—14 which are mounted inside of the autographic register casing. These two plates are flanged at the bottom as at 15 so that they can be fastened to the base of the register. Other means of mounting the feed mechanism may be employed if desired. There are two shafts 70 which extend across the register from one of the upright plates 14 to the other. The first of these is a feed shaft 16. This shaft carries two pin wheels 17 which are

keyed directly to the shaft by means such as cross pins. It also carries a pair of cam wheels 18, but they do not rotate with the shaft, the shaft merely providing a journal for them. The other shaft which extends from one upright 14 to the other is a crank shaft 19. This shaft is slightly below shaft 16 and spaced from it in the direction of oncoming forms. Shaft 19 is rotated once in each cycle of the register by means of a hand crank 20 which is located at the left side of the register outside of the case. In place of the hand crank a one cycle type of motor drive may be employed if desired.

There is a third member which extends crosswise of the machine, this being a hold-down bar 21 which is identical to the grip roller of the copending patent applications, being mounted in an identical way, but being arranged to be shifted into an elevated position where it is clear of the upper surface of the manifold forms being advanced through the machines during the feed cycle. The hold-down bar becomes functional only at the end of a complete cycle of the crank 20 when it is lowered and held down in form gripping position by means of one or more springs of the type shown at 20A in Figure 3 and illustrated diagrammatically only in Figures 4 and 5. In this gripping or clamping function of the hold-down bar 21 it performs the same function in the present feed mechanism that it does in the register of the copending applications. The bar is actuated by the two cam wheels 18. These wheels engage the bar adjacent to its opposite ends where rotatable sleeves 22 are provided so that the cams may roll upon them. Each cam has an arcuate indentation 23 cut into its outer circumference, which indentation provides a relief for the underside of the rotatable sleeve 22 in each case to permit the clamp bar to be pulled down into clamping position. At any other time when the indentations are out of line with the sleeve rollers, the hold-down bar is cammed up or raised to a point where it clears the forms.

This condition is shown in Figure 4. The clamped position of the bar 21 is shown in Figure 5. Clamping of the bar 21 takes place at the end of each complete feeding cycle which is the "home" position of the crank 20. The cam wheels therefore must rotate at a ratio of 1 to 1 with respect to the crank. This is accomplished by means of a gear 24 which is pinned to the crank shaft 19 and which is in mesh with a gear 25 secured to the side of the cam wheel, by means of a pin, so as to turn with it. The gears 24 and 25 are identical in size to provide the 1 to 1 ratio.

If manifolding forms of one particular length were to be used in the autographic register the pin wheels could also rotate at a 1 to 1 ratio with respect to the crank. As a practical matter the forms which must be fed through the register vary considerably in length from one user to the next, the specific length in each case being dependent upon the number of lines desired in the forms and other factors. Hence, one of the problems in the construction of the present feed mechanism is to provide a means of varying the ratio between the pin wheels and the crank to accommodate forms of different lengths while maintaining a constant 1 to 1 ratio between the cams and the crank. The answer to the problem is in the provision of a changeable gear ratio between the crank and the shaft 16 which does not affect the 1 to 1 ratio between the crank and the cams 18. The cams, being freely rotatably journaled upon the feed shaft 16, permit the latter shaft to be turned at any desired ratio, and thus, the pin wheels may be rotated to any extent desired during one cycle of the feeding operation. The crank shaft in the present case has a gear 26 keyed to it which is located immediately inside of the upright plate 14. This gear is in mesh with an idler 27 which is in turn in mesh with a gear 28 pinned to the outer end of feed shaft 16. Hence, the turning ratio of the crank relative to the feed shaft is directly dependent upon the ratio between the gears 26 and 28. Thus,

by changing either one or both of these two gears, the pin wheels can be rotated in one cycle to any extent desired so that long forms or short forms may be employed in the machine.

To facilitate changes in the ratios of gears 26 and 28 the idler gear 27 which is in between them is rotatably mounted on the shank of a journal bolt 29 which is engaged in an arcuate slot 30 through the upright wall 14. The arc 30 may be formed in several ways. In the present instance, it is centered upon the axis of feed shaft 16 which is also the center of gear 28. In this way the gear 26 can be provided in different sizes and with the gear 27 still in mesh with gear 28, the idler gear may be swung into a new position for meshing with a gear 26 of different size. If it is desirable to change gear 28 and not gear 26 the arc may be centered upon the longitudinal axis of the crank shaft 19 which is also the center of rotation of gear 26. In addition, a combination of both type slots may be employed in which case either one or both of the two gears 26 and 28 may be changed.

Following conventional practices a pawl 31 which may be pivotally mounted upon the upright wall 14 is engaged with the gear 28 so as to prevent the crank from being inadvertently turned in the wrong direction. Also following conventional practices the elements of the feed mechanism shown in Figures 4 and 5 are duplicated at the opposite sides of the autographic register machine. Also as described in copending patent application Serial No. 404,547, the clamp bar 21 may be swung up into an out of the way position to facilitate the loading of the register by pulling upon a finger tab 32.

Assuming that the register is loaded and that the hold-down bar is down into the form clamping position of Figure 5, the pins on the two feed wheels extend up through the holes in the forms and into annular relief grooves 33-33 which are provided adjacent to the opposite ends of the grip bar. The instant that the crank is turned the two cam wheels 18-18 are rotated to raise the clamp bar out of the indentations 23-23 so that the forms are free to be moved by the pin wheels. Since the two cam wheels are linked to the crank so that they rotate at a 1 to 1 ratio with respect to it, the feeding continues until the crank moves into "home" position which again brings the notches 23 into position below the hold-down bar 21 so that it drops down under the action of the springs to hold the forms securely in place. During this feeding operation the pin wheels are rotated through a number of degrees depending upon the ratio between gears 26 and 28. If the ratio between these two gears is 2 to 1, for example, the pin wheels may rotate twice. On the other hand, if the ratio is 1 to 2 the pin wheels may revolve only $\frac{1}{2}$ of a turn. Selecting other ratios obviously make it possible to accommodate forms of any desired length. It will be noted, however, that at no time during the feeding operation is there anything in contact with the forms to cause smudging.

Having described my invention, I claim:

An autographic register comprising a writing platen, a feed shaft, means rotatably journaled said feed shaft transversely of the register below the platen, a crank shaft, means rotatably journaled said crank shaft parallel to the feed shaft below the platen, a hold-down roller extending across the top of the platen parallel to and directly above the feed shaft, spring means urging said roller down into clamping relation with the platen, a pair of pin wheels keyed to the feed shaft in spaced relation to rotate together with the feed shaft, a pair of cam wheels, each cam wheel of the pair being freely rotatably journaled upon the feed shaft adjacent to, and to the outside of a pin wheel to rotate independently of the pin wheel, the cam wheels being of a size to contact the hold-down roller and prevent it from moving down into said clamping relation, each cam wheel having an indentation in its outer periphery configured to receive the hold-down

roller to permit the roller to move down into said clamping relation with the platen when the cam wheels are rotated into positions to present the indentations to the hold-down roller, gear drive means interconnecting the crank shaft and the cam wheels to drive the cam wheels in the ratio of one to one with respect to the crank shaft, whereby only once in each revolution of the crank shaft is the hold-down roller permitted to move down into said clamping relation, additional gear drive means interconnecting the crank shaft and the feed shaft, and the latter named gear drive means being changeable to provide

drive ratios for the pin wheels which vary with respect to the one to one ratio existing between the crank shaft and the cam wheels.
